UNITED STATES PATENT OFFICE.

EUCLID P. GOODCHILD, OF SPOKANE, WASHINGTON.

AUTOMOBILE-SIGNAL.

1,240,702.

Specification of Letters Patent. Patented Sept. 18, 1917.

Application filed January 15, 1917. Serial No. 142,494.

To all whom it may concern:

Be it known that I, EUCLID P. GOODCHILD, a citizen of the United States, and a resident of Spokane, in the county of Spokane and State of Washington, have made certain new and useful Improvements in Automobile-Signals, of which the following is a specification.

One of the principal objects of my invention is to provide an improved automobile signal formed to represent a human hand, which is so constructed that it may be operated from the inside of a closed car for signaling an intended stop or turn, to approaching vehicles or pedestrians.

Another object of the invention is to provide an improved automobile signal which may be actuated very quickly so that in time of emergency a quick signal may be given, and without necessitating the operator moving from his usual driving position.

A still further object is to provide an improved signal of the class described which will be extremely simple, durable and efficient in operation and inexpensive to manufacture.

The invention is hereinafter described, and illustrated in the accompanying drawing, in which—

Fig. 1 represents a view in perspective of an automobile signal constructed according to my invention showing the same in place on one of the sides of an automobile.

Fig. 2 represents an end elevational view of the device.

Fig. 3 represents a view in section taken vertically and longitudinally on the plane indicated by the line 3—3 of Fig. 2.

Fig. 4 represents a view similar to Fig. 3 showing the signal in operative position, and

Fig. 5 represents a fragmentary perspective view of the movable frame and adjacent parts.

In carrying out my invention in practice, I provide a cylindrical casing 5 open at its outer end and closed at its inner end as at 6, such casing being secured to the upper end of a bracket 7, the latter being provided with offset ears 8 whereby it may be secured by suitable fasteners to one of the sides,—or other proper point on the vehicle.

The cylinder is adapted to house and protect the movable parts of the signal while they are in inoperative position. The signal proper includes a frame 9, substantially

rectangular in shape, the lower side 10 of which is guided for movement in a clip 11 supported on the outer end of an arm 12, which arm in turn is movable longitudinally of the cylinder 5 through a guide 13 secured on the lower wall of the cylinder. The inner end of arm 12 is turned upwardly as at 14 to provide a stop for the outward movement of the signal into operative position.

Between the inner wall 15 of frame 9, and the closed end 6 of the cylinder is interposed a spiral spring 16 which exerts a constant tension upon the frame 9, tending to force the latter outwardly from the cylinder.

The outer wall 16 of the frame 9 is provided with a series of openings as at 17 through which a strip of metal indicated generally at 18 is passed and repassed, to form representations of the fingers and thumb of a human hand as clearly shown in the drawing. The upper portion of the front wall 16 of frame 9, is offset inwardly as at 19 so as to increase the resemblance of the device to a human hand. The various loops of the metallic strip are slideable through the openings in the front wall 16, and certain of the inner loops 20 are soldered or otherwise suitably secured to a cross head 21 which is arranged within the frame 9 and is slideable on a pin 22 secured to the rear wall of the frame and extending axially of the latter. Interposed between the rear wall 14 of the frame and the cross head 21, is a spiral spring 23 whose tendency is to force the cross head outwardly whereby to move the fingers and thumb into extended position as indicated in Fig. 4. It will be noted that the terminals of the strip 18 forming the fingers and thumb of the device are not secured to the frame, but are unattached so that no impediment to the ready movement of the fingers and thumb inwardly and outwardly through the openings in the frame wall is encountered.

A plurality of flexible elements 24 are secured at their outer ends at points on the cross head 21 equally spaced around the pin 22, and these flexible elements are led back through openings in the rear wall 15 of the cross head, and then drawn together and directed through an opening 25, cut in the cylinder and are directed over a pulley 26 and terminate with a knob 27 by which the device may be manipulated. At a suitable point in their length the flexible elements

are knotted together as at 28, and when the device is in retracted or inoperative position, this knot engages in a notch 29 cut in the lower off-set end 30 of the bracket 7 as indicated in Fig. 1 for retaining the movable elements of the device within the cylinder against the tension of springs 16 and 23. When it is desired that the signal be brought into operation, the handle 24 may be grasped and pulled sufficiently outwardly to release the knot 28 from notch 29, and upon such release the springs will force the parts outwardly to the position indicated in Fig. 4. To move the signal into inoperative position it is simply necessary to pull down the knob and engage the knot in the notch 29.

The device is susceptible of being brought into instant use by simply disengaging the knot and this advantage will be found to be of great assistance in emergency where a quick signal is to be given to approaching or trailing vehicles. Furthermore, the arrangement is such that the cylinder may be mounted on a closed car in such manner as to extend through an opening in the car so that the signal may be readily operated from within the vehicle.

I claim:—

1. A signal for the purpose specified, comprising a cylinder adapted for attachment to a vehicle, a metal frame which is movable into and out of said cylinder, a slidable stop which is operatively connected with the cylinder and said movable frame, fingers

secured to the latter and adapted to be projected therefrom to serve as a signal proper, a guide pin held in the movable frame and whereon the said fingers are adapted to slide, a spring applied to said pin and tending to project the fingers forward, another and stronger spring arranged between the cylinder head and movable finger-carrying frame, and means for manually locking and releasing the frame, as shown and described. 35

2. A signal for the purpose specified, 45 comprising a cylinder adapted for attachment to a vehicle support, a frame slidable therein and having its front end provided with a series of openings, a metal strap passing back and forth through said openings and its convolutions extending forward to serve as a signal proper, and means for protecting the said signal from the cylinder, as described. 50

3. A signal for the purpose specified, 55 comprising a cylinder, a skeleton frame slidable therein, a cross head slidable in the skeleton frame and having a series of fingers projecting forwardly therefrom to serve as the signal proper, a guide pin fixed in the skeleton frame and whereon the cross head is slidable, an ejecting spring applied to said pin, and means for projecting and retracting the signal, as shown and described. 60
